Filed Jan. 30, 1956, Ser. No. 562,055

1 Claim. (Cl. 313—82)

This invention relates to image reproduction devices and more particularly to picture tubes employed in such devices as, for example, television apparatus.

The source of electrons for the writing beam utilized to form the image on a picture tube viewing panel is provided by a cathode which is assembled on an electron gun mount along with electron accelerating and beam modulating electrodes. In an electrostatic focusing type picture tube, the electron beam focusing electrodes are also mounted as an integral part of the gun structure.

Generally, these gun mount electrodes are positioned and aligned relative to one another by means of several ceramic rods cooperating with integral pins or bands connected to or around the electrodes. The ceramic rods are disposed about the periphery of the electrodes and extend longitudinally along the gun mount. Due to the necessity of centering the electron beam after removing the ions from the electron beam, the electrode assembly is positioned so that its longitudinal axis intersects the longitudinal axis of the neck portion of the tube. An electrostatic lens and an ion trap magnet causes the ions to be removed from the writing beam in a manner well understood in the art.

The electrostatic lens assembly of the uni-potential type generally employed to focus the electron beam in an electrostatic focus type picture tube conventionally comprises first and second lens electrodes spaced apart along the path of electron travel with a lens ring interposed between and circumscribing the lens electrodes. These lens elements are each provided with pins which are attached to ceramic rods so that they form an initial sub-assembly which is subsequently mounted upon a second electrode sub-assembly generally consisting of the cathode, first and second grids and the first anode electrode. The leading edge of the first anode usually lies in a plane which intersects, if extended, the extended plane of its trailing edge, and the longitudinal axis of the above described second electrode sub-assembly is conventionally different from the longitudinal axis of the focusing electrode sub-assembly. These electrode positions and configurations are used to provide the electron path necessary to properly remove the ions and direct the beam back to its correct position.

The lens electrodes are formed with a hollow cylindrical body portion terminating at one end in a smaller diameter cylindrical portion. A tapered shoulder which is formed as part of the lens electrode connects the body portion with the smaller diameter portion. The larger end of the electrodes are open, while the reduced portion is closed off by an end plate. This plate is formed to provide a flat ring of material circumscribing a depression having an aperture centrally disposed therein.

During the lens sub-assembly construction operation, the first and second lens electrodes and the lens ring are positioned in axial alignment and the lens electrodes are moved relative to one another until they are correctly spaced. This dimension is measured between the oppos-

ing flat rings on the end plates of the first and second lens electrodes.

Due to the configuration of the lens electrode end plates, it is difficult to construct these parts with consistent accuracy. In addition, accurate measurement of the distance between the flat rings when they are disposed inside the central lens ring is not conveniently and efficiently attained. These disadvantages combine to cause many finished tube rejects which are due to the non-acceptable operating electrical characteristics of the tubes caused by improper electrode spacings.

Accordingly, it is an object of the invention to reduce the aforementioned disadvantages and to provide an improved cathode ray tube electrode structure.

A further object is the provision of a simplified electrode gun structure.

A still further object is to provide an electron gun assembly having a structure which lends to the production of an improved cathode ray tube and to simplified construction methods.

The foregoing objects are achieved in one aspect of the invention by the provision of a straight cathode ray tube electrode assembly which includes beam modifying electrodes formed as cylinders having a main body portion and a smaller diameter terminal portion connected by a shoulder lying substantially normal to the cylinder axis. The first lens electrode in the lens assembly is formed as a section of the first anode electrode for the tube to facilitate a simplified structure.

For a better understanding of the invention, reference is made to the following description taken in conjunction with the accompanying drawings in which:

Fig. 1 is a sectioned view of a portion of a cathode ray tube employing an electron gun mount formed in accordance with one aspect of the invention; and

Fig. 2 is a partially sectioned perspective view of the electrodes employed in the electrostatic focusing assembly utilized in the gun structure shown in Fig. 1.

Referring to the drawings, a cathode ray tube 11 is provided with a face plate 13, and a neck portion 17. The cathode ray tube is hermetically sealed by wafer 19 and exhaust tubulation 21. Disposed on the internal surface of face plate 13 is the electron responsive fluorescent material 23. Mounted in neck portion 17 is the electron gun structure 25 which provides the source, acceleration, modulation, and focusing of an electron beam. An electrically conductive coating 27 is applied to the internal surface of the neck 17 and flared portion (not shown) to form an electrode which carries a high potential for accelerating the electrons toward the fluorescent material layer 23.

The electron gun structure assembly 25 is mounted within neck portion 17 by means of support tabs 29 and snubbers 31. The axis of the gun assembly is disposed at an angle of approximately 3 degrees with the longitudinal axis of the tube so that the electron beam will be directed generally towards an extended portion of the tube neck. This directed beam is operated on by the slashed lens formed by the trailing edge of second grid 33 and the leading edge of first anode 35, and by an ion trap magnet 37 positioned outside of the tube neck to remove the heavy ions from the electron beam and to return the beam to its operative position along the axis of the tube.

The modulating voltages for the writing beam are normally applied to the circuit including the cathode and grid 31, while grid 33 and anode 35 serve to accelerate the electrons during the scanning period in addition to providing the beam deflection field for removing the ions as described above. In an electrostatic focus type picture tube such as the embodiment illustrated in

the drawings, the terminal section 39 of anode 35, along with lens ring 41 and lens cup 43 serve to accelerate the electrons and to focus the electron beam. Anode 35 is formed as a straight cylinder to provide a common axis for all electrodes. Horizontal and vertical deflection coils 45 provide the means for scanning the focused and modulated beam over the fluorescent panel 23 to reproduce the transmitted image.

Referring particularly to Fig. 2, the electrostatic focusing sub-assembly electrodes are shown in their operable positions. The first lens cup 39 is formed as part of anode 35 so that the lens cup, which has a smaller diameter than the anode, extends forward in the direction of electron travel. The second lens cup 43 has a smaller diameter terminal portion with a configuration corresponding to that of lens cup 39. The opposed surfaces of these lens cups are formed with depressions 51 having apertures 53 centrally disposed therein. The electrons traveling along the longitudinal axis of the tube passes through these apertures, with the primary focusing action of the electron beam being affected by the electrostatic field existing in the space circumscribed by lens ring 41 between the opposed surfaces of lens cups 39 and 43. The shoulder section 55 interconnecting the larger and smaller diameter portions of the lens cups 39 and 43 lie substantially perpendicular to the longitudinal axis of the electrodes. The axis of the lens cups and lens ring lies along the axis of the accelerating and modulating electrodes to provide a straight electrode mount.

The spacing between the opposed faces of lens cups 39 and 43 is critical and must be maintained to assure a proper focusing action. Since the opposed lens cup faces are disposed within the lens ring 41, it is difficult to provide means for gauging the spacing between these surfaces during assembly. The shoulders 55 formed on the lens cups 39 and 43 thereby provide an accurate and efficient means for positioning these electrodes. During assembly, the three lens elements along with the other electrodes are placed in a jig having depressions which cooperate with the surfaces of the electrodes including the surfaces of lens ring 41 and the shoulders 55 to correctly position them while ceramic beads 47 are applied to the studs 49 to affix these electrodes together.

Lens electrodes constructed in accordance with the aspect of the invention illustrated are more economical since the first anode 35 and lens cup 39 are formed as one straight electrode instead of the previously used two

separate electrodes. Also, an electrode gun mount employing this structure is more rigid and adaptable for more efficient assembly methods since the same several support beads affix the entire electrode assembly together.

5 This configuration of electrodes enables a simplified straight electrode assembly to be constructed. In addition, the provision of straight shoulders on the lens cups affords an improved method of spacing these electrodes from one another.

10 Although several embodiments of the invention have been shown and described, it will be apparent to those skilled in the art that various changes and modifications may be made therein without departing from the scope of the invention as defined by the appended claim.

15 What is claimed is:

An electrostatic focus type electrode assembly adapted to be employed in a cathode ray tube having an envelope with a neck portion and an image display screen spaced therefrom comprising, in sequence, an electron emitter, 20 an accelerating electrode, and electrostatic beam focusing electrodes including a first lens element formed as part of said accelerating electrode, a lens ring and a second lens element, said first and second lens elements having a cylindrical body portion formed with a smaller diameter cylindrical terminal portion and a shoulder interconnecting said body portion and said terminal portion lying in a plane substantially normal to the axis of said lens elements, said terminal portions being partially disposed within said lens ring, and support rods for said electrical assembly, said electron emitter, accelerating electrode and beam focusing electrodes being axially aligned with one another and mounted upon said support rods, said support rods being common to all the parts of said assembly and within the neck portion.
